(57) **CLAIM**

The ornamental design for a thermometer as shown and described.

DESCRIPTION

FIG. 1 is a front, right side, perspective view of a thermometer showing our new design;

FIG. 2 is a front view thereof;

FIG. 3 is a rear view thereof;

FIG. 4 is a left side view thereof; a right side view is omitted because it is mirror image of the left side view;

FIG. 5 is a top view thereof;

FIG. 6 is a bottom view thereof;

FIG. 7 is a front, right side, perspective view thereof, shown in a state of use; and,

FIG. 8 is a rear view thereof, shown in a state of use.

The broken lines are included for the purpose of illustrating environment in FIG. 7 and portions of the thermometer in FIG. 8 and form no part of the claimed design.
